UNITED STATES PATENT OFFICE.

EDWARD B. HESS, OF NEW YORK, N. Y., ASSIGNOR, BY MESNE ASSIGNMENTS, TO
ROYAL TYPEWRITER COMPANY, INC., OF NEW YORK, N. Y., A CORPORATION
OF NEW YORK.

RIBBON MECHANISM FOR TYPE-WRITING MACHINES.

1,130,401.

Specification of Letters Patent.

Patented Mar. 2, 1915.

Application filed June 15, 1912. Serial No. 703,772.

To all whom it may concern:

Be it known that I, EDWARD B. HESS, a citizen of the United States of America, residing in the borough of Brooklyn, city and State of New York, have invented a certain new and useful Improvement in Ribbon Mechanism for Type-Writing Machines, of which the following is a specification.

This invention relates to bi-chrome ribbon mechanism and makes provision for printing from different zones of a ribbon, as, for instance, black and red, when a printing operation by depression of a so-called "silent" key is effected.

15 The invention is shown as applied to the organization disclosed in the patent of J. F. McBirney, No. 1,010,290, of November 28, 1911, and may therefore be considered, in a sense, as an improvement upon the construction disclosed in that patent.

20 The invention comprises in connection with ribbon mechanism of variable extent of movement, an organization in which the ordinary printing keys 25 are connected with the universal bar by permanent mechanical connections, and in which the silent or accent keys are connected by permanent mechanical connections, with transversely arranged means for 30 operating the ribbon vibrator without actuating the escapement. The ribbon mechanism is adapted to be adjusted to print from either the upper or lower zone of the ribbon.

35 In the accompanying drawing: Figure 1 is an elevation of the right hand side of the machine with the side plate removed and some parts in section: Figs. 2, 3 and 4, respectively, side elevations of the ribbon mechanism as seen at the right hand end of 40 Fig. 1, the parts being shown in varying positions: and Fig. 5, a rear view showing the universal bar, its suspending frame and some parts carried thereby.

45 So far as the machine illustrated corresponds with that shown in the above mentioned patent of McBirney it will not be described. It is thought to be sufficient to describe in detail only those changes that constitute the present invention.

50 Turning on the transverse shaft 1 are pendant arms 2, 3, located respectively adjacent the sides of the machine. These arms are connected intermediate their length by a

cross bar 4 and between their ends extends the universal bar 5. Intermediate the pendant arms 2, 3, there is fixed on bars 4 and 5 a vertical plate 6, on the upper end of which extending above the bar 4 is pivoted a swinging pendant plate 7 recessed or cut away at 8 to afford clearance for the bar 4. 60 The pivot bolt 9 of the arm 7 has wound around it a spring 10 one end of which is engaged with the edge of the fixed plate 6 and the other with the swinging arm 7, the reaction of the spring being such as to cause 65 the arm adjacent its lower end to be held in contact with an adjustable screw stop 11 carried by a right-angular extension 6' of the fixed plate 6. The swinging plate 7 is offset, as seen in Fig. 5, so that 70 there is between it and the fixed plate 6 a substantial space 6''. Fixed to the swinging plate 7 by means of a clamp nut 12 is a bolt 13 that passes through the swinging plate and projects into or across the space 75 between the plates 7 and 6. This bolt or pin is circular except that it is cut away or flattened on one side.

Above the adjustable stop 11, the plate 7 has a forwardly projecting part 7' adapted 80 to be engaged by a wiper 14 that connects the transverse rock shaft 15 of the silent key devices and the shaft 16 around which the silent key links 17 are hooked. As shown in the above mentioned McBirney patent the 85 rock shaft 15 has its bearings in brackets 15' on the frame of the machine and has fixed to it a plurality of arms 14 which carry in their ends the transverse rod 16. The rod 16 extends on either side of the longitudinal center of the machine, and may receive the hooked ends of a plurality of silent key links 17. The arm 14 disposed at the center of the machine is herein called a wiper arm and acts directly on the projection 7' of the 95 swinging plate 7. Instead of a transverse rod 16 (and as disclosed in the McBirney patent) there may be secured to the rock shaft the above mentioned wiper arm and on each side thereof as many arms as are 100 required for the silent key links—one for each link. Similar links 5' corresponding with the ordinary printing keys of the machine are hooked around the universal bar 5.

105 18 is the forwardly extending arm of the ribbon vibrator operating bell crank and 19

is its downwardly extending arm pivoted to which intermediate its ends is a horizontally disposed lever 20 whose forward end is connected by an upwardly extending link 21 to a rotatable block 22 having flat faces with which a flat positioning spring 23 co-operates. By rotation of the block 22, the forward end of the lever 20 may be raised and lowered to correspondingly raise and lower its rear end. The rear end of the lever 20 is widened vertically, extends into the space 6² between plates 7 and 6 and has two surfaces 24, 25 located in different planes that co-operate with the actuating transverse pin or projection 13 to effect different ranges of movement of the ribbon vibrator to cause printing from the upper or lower zone of a ribbon vibrator. The circumferential faces of different radius of block 22 serve as stops against which the bell crank arm 19 abuts. Partial rotation of the block brings its proper stop surface into position and simultaneously, through link 21, correspondingly adjusts the lever 20. Any suitable means for adjusting the block may be adopted, as for instance that shown in Letters Patent No. 984,671 granted February 21, 1911 to Edward B. Hess. In that patent as in the present invention the rotatable or rocking block 22 has stop faces that are co-incidentally adjusted with the lever 20 and operate to positively arrest the ribbon operating bell crank when either zone of the ribbon is being printed from.

In Fig. 1 all the parts are shown in normal position.

In Fig. 2, the universal bar is shown as having moved forward and the actuating projection 13 has just engaged the surface 25 of the lever arm 20 and is about to move it endwise to effect operation of the ribbon vibrator.

In Fig. 4 the parts are shown in the normal position, the same as in Fig. 1; whereas in Fig. 3, the part or wiper 14 carried by the rock shaft 15 and transverse shaft 16 of the silent key mechanism has moved forward and acted upon the projection 7' of swinging plate 7 and brought the actuating projection 13 into engagement with surface 25 of link 20 and on further movement the ribbon vibrator will be actuated. It therefore appears that printing from the upper zone of the ribbon may be effected on the actuation of the silent keys as well as on actuation of the remainder of the keys of the machine. If, however, lever arm 20 is so adjusted that its face 24 farthest from its axis is in operative relation to the actuating projection 13, a greater extent of movement will be imparted to the ribbon vibrator and printing may therefore be effected from the lower zone of the ribbon. Adjustment of the block 22 and therefore of the lever arm 20 may be effected in any appropriate way as

for instance, in the manner shown in the above mentioned patent of Edward B. Hess or otherwise. Of course, when the universal bar is drawn forward, the lower end of swinging plate 7 is in contact with the adjustable stop 11 and is therefore carried forward with the universal bar. When, however, plate 7 is actuated by wiper 14, the universal bar and its frame remain stationary and the swinging plate 7 is moved forward out of contact with the stop screw. Mounted centrally on the swinging universal bar frame is an upwardly extending arm or plate 26 that contacts with the stop screw 27 of escapement rocker arm 28. When, therefore, the universal bar is drawn forward, the escapement is operated. When, however, printing from silent keys is being effected the escapement remains inoperative.

I claim—

1. A typewriting machine comprising the combination of type bars, type bar operating connections, keys therefor, most of the keys being ordinary printing keys and some of them "silent" keys, a swinging universal bar, permanent mechanical operating connections connecting the ordinary printing keys and the universal bar, silent key devices and permanent operative connections connecting the same with the silent keys, bi-chrome ribbon mechanism, means for adjusting it to effect printing from either an upper or lower zone of a ribbon and means whereby printing may be effected at will from either zone of the ribbon whenever a "silent" key or an ordinary printing key is operated.

2. In a typewriting machine having ordinary printing keys whose operation is accompanied by feed of the carriage and "silent" keys whose operation is unaccompanied by feed of the carriage, bi-chrome ribbon mechanism, a swinging universal bar frame, a swinging plate pivoted on the universal bar frame and adapted to act upon the bi-chrome ribbon mechanism when the universal bar frame is operated and also independently of movement of the universal bar frame, and a part actuated by the "silent" keys to move said swinging plate and effect actuation of the ribbon mechanism without moving the universal bar.

3. In a typewriting machine having ordinary printing keys and "silent" keys, the combination of a universal bar, a swinging universal bar frame comprising pendant swinging arms in which the universal bar is mounted, a swinging plate mounted on the universal bar frame and movable with the universal bar and adapted to actuate ribbon mechanism independently of the universal bar, means for actuating the universal bar and its swinging frame when ordinary printing keys of the machine are depressed and means for actuating the swing-

ag plate without actuation of the universal
bar when "silent" keys of the machine are
operated.

4. In a typewriting machine, the combination of a universal bar, a swinging frame comprising pendent arms in which the universal bar is mounted, a transverse rod connecting said arms above the universal bar, a fixed plate carried by the universal bar and said transverse bar, a swinging plate pivoted on the fixed plate and adapted to move with and also independently thereof for the purposes described.

5. The combination with ribbon-mechanism of a typewriting machine of a univer-

sal bar and a ribbon-mechanism actuating member mounted on the universal bar and movable therewith to actuate the ribbon mechanism whenever a printing key is depressed, and means for operating said actuating-member independently of the universal bar whenever a "silent" key is depressed. 20

In testimony whereof, I have hereunto subscribed my name.

EDWARD B. HESS.
